UNITED STATES PATENT OFFICE.

CHARLES ARTHUR MESTRE AND EMILE EUGÈNE HENRI DUCHATEL, OF PARIS,
FRANCE.

SUPERHEATING ELEMENT.

Application filed May 13, 1924, Serial No. 713,040, and in France May 18, 1923.

The superheaters of locomotive boilers consist as a rule of tubular elements disposed within the large smoke tubes of the boiler; the said elements are connected at 5 one end with a steam drum disposed in the smoke box and receiving the steam from the boiler, and at the other end to a second steam drum (or to another chamber of the same drum) supplying the superheated steam to 10 the engines.

The present invention relates to a superheating element for locomotive boilers which is entirely contained within a smoke tube and comprises flat tubes in parallel disposition, said tubes being traversed by the steam in one direction, and a cylindrical tube for the return of the superheated steam to the superheated steam drum.

The following description and appended 20 drawings which are given by way of example set forth the present invention.

Figs. 1 to 7 relate to a superheating element, comprising four flat tubes for one direction of flow and a circular tube for the 25 other direction.

Fig. 1 is a vertical transverse section of a smoke tube and of a superheating element.

Fig. 2 is a transverse section of four flat tubes showing their junction by welding at 30 each end of the same.

Figs. 3 and 4 show the box for assembling the four flat tubes either with the cap on the side next the furnace, or with a circular tube on the side next the steam drum.

Figs. 5 and 6 show a lengthwise section 35 and a plan view of the superheating element on the side next the fire box.

Fig. 7 is a lengthwise section of the superheater element on the side next the smoke box.

As observed in the figures, the superheating element consists of four flat tubes a^1 , a^2 , a^3 , a^4 in parallel disposition in a vertical plane; the two outer tubes of the group may 45 have the opposite ends thereof bent upwardly and preferably these two tubes have the opposite ends thereof bent inwardly toward the two inner tubes as shown in Figs. 1, 5 and 7. The four tubes are thus substantially parallel at the central portions thereof, the central portions of the two outer tubes being somewhat below the plane of the two inner tubes, while the opposite ends of the tubes are welded together, as shown in 55 Fig. 2. On the side of the inlet of wet

steam, in the direction of the arrow A, Fig. 7, the four tubes are connected with the steam drum by a junction element b which is shown on a larger scale in Figs. 3 and 4. On the side next the fire box, Figs. 5 and 6, the four tubes are connected either with a cap d of the known type through the medium of a junction piece analogous to the element b . The junction piece b and the cap of a known type can be in one piece, 60 welded, as in Fig. 5, on one side of the four tubes and on the other side to the return tube e . The superheating element as a whole is disposed within a smoke tube, as 65 shown in Fig. 1.

The following advantages are offered by the said arrangement in accordance with the invention.

1. The steam flows through the element 70 only once in the forward direction—from the smoke box towards the fire box—and once in the back direction—from the end next the fire box towards the smoke box, thereby reducing the losses of steam pressure when traversing the element.

2. The said element offers a large superheating surface in the forward direction, i. e. in the direction in which the steam encounters gases which have a greater heat according as the steam becomes superheated, 75 due to the use of flat tubes in parallel disposition wherein each tube is traversed by a fraction of the steam to be superheated; the use of the flat tubes permits of a considerable increase in the superheating surface, 80 without diminishing the flow section of the gases, and this will offer a great increase in the efficiency of the element.

3. The flat tubes are placed preferably in the vertical position i. e. with their flat walls 85 vertical, as shown in Fig. 1, so as to reduce to a minimum the liability of clogging by the smoke and to facilitate the cleaning.

4. The return of the steam will take place 90 as directly as possible, through a cylindrical tube which thus offers the minimum surface for a given internal cross section, so as to reduce the heat losses in the portion in which the temperature of the steam exceeds the 95 temperature of the gases flowing upon the 100 tube.

The number of the flat tubes, their external 105 and internal dimensions, and the dimensions of the cylindrical return tube should be so combined as to obtain the maximum effi- 110

ciency, taking account of the internal diameter of the large smoke tube in which the said element is to be disposed. The accompanying drawings show by way of example 5 an element comprising four flat tubes. A greater or less number of flat tubes may be employed.

What we claim is:

1. A superheater comprising a set of flat 10 tubes, a return tube circular in cross-section and extending in parallelism with said set of tubes, and means comprising junction boxes uniting one end of said set to said return tube and adapted to unite the other end of 15 said set to a saturated steam conduit.
2. A superheating element for a boiler, comprising a set of flat tubes through which steam is circulated, said tubes being spaced apart at the middle and placed with their 20 flat faces in contact at the ends, a return tube, means connecting one end of the set of

flat tubes with one end of said return tube, and means connecting the other end of the set of flat tubes with the steam drum of said boiler.

3. A superheating element for a boiler, comprising a set of flat tubes through which the steam is circulated, said tubes being spaced apart at the middle and placed with their flat faces in contact at the ends, a circular return tube disposed substantially parallel with said set of tubes, a junction box which is quadrangular at one end and circular at the other end for connecting one end of the flat tubes with one end of said return tube, and means connecting the other end of the set of flat tubes with the steam drum of said boiler.

In testimony whereof we have signed this specification.

CHARLES ARTHUR MESTRE.

EMILE EUGÈNE HENRI DUCHATEL.
